WEB CUTTING MECHANISM

Wesley P. Shomaker, Richmond, Va.

Application June 22, 1938, Serial No. 215,255

2 Claims. (Cl. 164—43)

My invention consists in new and useful improvements in a web cutting mechanism for use in continuous feed, power-operated machines, and is primarily directed to a patch cutting device for severing from a web of transparent material, strips for application to window-type envelopes.

It is the object of my invention to provide a strip cutting mechanism of this type wherein a continuously fed web may be severed at intervals without interrupting or obstructing the continuous feed of the web.

Another object of the present invention resides in the structure and operation of the knife whereby the latter, after severing a patch or strip, is automatically tilted in the direction of travel of the web so as to prevent the curling up of the advancing edge of the web, after which said knife is slowly returned to normal position.

A further object of my invention is to provide a cutting knife and operating cam arrangement whereby the knife is subjected to a minimum of shock and strain, thus prolonging the life and utility of the knife.

A still further object of my invention is to provide a web cutting mechanism including a horizontal stationary knife and a perpendicular movable knife mounted on arms adapted to swing in an arc, said movable knife being provided with a secondary fulcrum and means co-acting therewith to compensate for the arcuate movement of said supporting arms, whereby the shearing action is maintained substantially perpendicular.

With the above and other objects in view which will appear as the description proceeds, my invention resides in the novel features herein set forth, illustrated in the accompanying drawings and more particularly pointed out in the appended claims.

Referring to the drawings in which numerals of like character designate similar parts throughout the several views,

Fig. 1 is a perspective view of my improved strip cutting mechanism, showing the knife and cams in non-cutting positions.

Fig. 2 is a transverse section of the same, showing a continuous web being fed through the mechanism, with the parts in the positions shown in Fig. 1.

Fig. 3 is a similar view showing the parts in cutting position, and

Fig. 4 is a fragmentary view similar to those just referred to but showing the knife in tilted position which immediately follows the cutting position.

In the drawings, 1 represents a base or block in

which is preferably inset a horizontal stationary knife 2 of any suitable metal. A reciprocating knife 3 perpendicular to said stationary knife and adapted to cooperate therewith, is secured to a knife bar 4 by means of screws 5 or other suitable means, with its free cutting edge normally in line for shearing engagement with the cutting edge of the stationary knife 2. The knife bar 4 is rotatable and for this purpose may be mounted on an axle or shaft 6 which projects therefrom at both ends where it is supported by the free ends of pivoted arms 7 and 8, the latter being in turn pivotally mounted on a longitudinally extending shaft or rod 9 carried by the machine proper.

On the knife bar 4 adjacent one end of the reciprocating knife 3, I provide a stop plate 10 which extends a predetermined distance below the free edge of the knife 3 and is adapted to normally abut the cutting edge of the stationary knife 2 to insure proper shearing alignment of the two knives. As heretofore pointed out, the knife bar 4 is rotatably supported with respect to the arms 7 and 8, and in order to normally maintain the cutting knife 3 in shearing alignment, I provide springs 11 which tend to maintain the abutment of the stop plate 10 with the edge of the stationary knife 2. Although any suitable spring means may be employed for this purpose, those shown in the drawings consist of coil springs at each end of the shaft 6, one end of each spring being fixed to the shaft and the other end engaging the knife bar 4 to cause a rotary tension thereon.

Similar springs 12 may be employed on the shaft 9 for normally lifting the arms 7 and 8, to maintain the knives 2 and 3 out of engagement.

A rotary shaft 13 operatively connected in any suitable manner to the motive power of the machine proper extends longitudinally above the reciprocating knife bar 4 and carries a pair of cams 14 and 15, one adjacent each of the arms 7 and 8, said arms being provided with rollers 14a and 15a arranged in line for engagement by the respective cams. These cams are so designed and positioned on the shaft that the raised portion of cam 15 is preferably slightly in advance of the raised portion of cam 14, whereby upon the rotation of the shaft 13, the end of the reciprocating knife 3 adjacent the cam 15 cuts slightly in advance of the other end, thereby affecting a shearing action on the web.

Intermediate the cams 14 and 15 on the shaft 13 I provide a tilting cam 16 adapted to cooperate with a roller 17 carried by an upwardly extending

arm 18 on the knife bar 4. It will be noted that the tilting cam 16 is timed with respect to the cams 14 and 15 so as to operate immediately upon the completion of the cutting action of the knife 3 to instantly tilt the knife 3 outwardly by rocking the cutter bar 4 on its shaft in opposition to the action of the springs 11. The forward edge 16a of the cam 16 is abrupt to insure immediate action in tilting the knife 3, but the rear or trailing edge 16b of said cam very gradually recedes so as to retard the return of the knife 3 to normal position by the springs 11 and thus prevent a sudden shock which would otherwise occur when the stop plate 10 contacts the forward edge of the stationary knife 2.

This patch cutting mechanism is installed adjacent the feed rolls (not shown) of the machine with which it is to be used, and the shaft 13 is operatively connected in any suitable manner to the motive power of the machine so as to operate in timed relation with the feed of the web W.

In operation, the web W is fed past the stationary knife 2 at any predetermined speed and as the shaft 13 rotates in the direction of the arrow (Figs. 2 and 3), the cams 14 and 15 intermittently cause the knife 3 to shear patches from the web, the springs 12 on the shaft 9 causing the return of the knife 3 after each cutting operation. Immediately upon the conclusion of each down-stroke of the knife 3, the forward face 16a of the tilting cam 16 engages the roller 17 on the upwardly extending arm 18 which rotates the knife bar 4 and tilts the knife 3 in a direction away from the stationary knife, thereby preventing the advancing edge of the continuously fed web from curling up behind the knife 3. This operation takes place simultaneously with the lifting of the arms 7 and 8 by the springs 12, and by the time the knife 3 has assumed its uppermost position, the operation of the tilting cam 16 and springs 11 has begun to slowly return the knife 3 to its normal position ready for the next down-stroke. As before stated, the contour of the trailing edge 16b of the cam 16 insures the gradual return of the knife 3 to normal position without permitting a sudden shock when the stop plate 10 contacts the forward edge of the stationary knife 2 under the tension of the springs 11. Repeated shocks during the rapid operation of this machine would tend to twist the knife and cause the same to become out of alignment with the edge of the stationary knife 2.

It will also be noted that the pivotal connection of the reciprocating knife 3 and knife bar 4 with respect to the free ends of the arms 7 and 8, and the constant tension of the springs 11, insures a substantially perpendicular cutting ac-

tion of the knife. In other words, the fact that the arms 7 and 8 are pivoted to the rod or shaft 9 would normally cause the knife bar and knife to describe an arc. However, with the knife bar pivoted or rotary on the ends of the arms 7 and 8 and the normal engagement of the stop plate 10 with the forward edge of the stationary knife 2, the arc described by the arms 7 and 8 is compensated for and the substantially perpendicular cutting operation of the knife 3 is insured, and locking or jamming of the movable knife against the stationary knife is prevented.

From the foregoing it is believed that the construction and advantages of my improved web cutting mechanism may be readily understood by those skilled in the art without further description, it being borne in mind that numerous changes may be made in the details disclosed without departing from the spirit of my invention as set out in the following claims.

What I claim and desire to secure by Letters Patent is:

1. Web cutting mechanism including a stationary knife, a pair of arms pivotally mounted above said stationary knife, a cross bar rotatably supported at the free ends of said arms, a shearing knife carried by said cross bar, spring means tending to normally maintain said arms in raised position, rotatable cam means for intermittently depressing said arms and shearing knife against the tension of said spring means, to effect a shearing action with said stationary knife, a stop and guide abutment carried by said cross bar adjacent one end of said shearing knife and extending beyond the cutting edge of the latter, means cooperating with said cross bar for yieldably maintaining said abutment in engagement with the cutting edge of said stationary knife, whereby the arcuate movement of said pivoted arms is compensated for to maintain said shearing knife substantially perpendicular to said stationary knife during its downward movement, a second rotatable cam arranged in timed relation with said first named cam means and operatively associated with said cross bar, for rapidly rotating the latter in a direction to tilt said movable knife away from said stationary knife upon the completion of each down-stroke, and means on said second cam for retarding the return movement of said shearing knife to prevent sudden impact of said abutment with said stationary knife.

2. Web cutting mechanism as claimed in claim 1 including a tilting arm on said cross bar projecting into the path of rotation of said second cam, for tilting and retarding the return movement of said shearing knife.

WESLEY P. SHOMAKER.
